(57) **CLAIM**

The ornamental design for a racket throat, as shown and described.

DESCRIPTION

FIG. 1 is a front perspective view of a racket throat showing my new design;

FIG. 2 is a front view thereof, the rear view being a mirror image of the front view;

FIG. 3 is a left side view thereof, the right side view being a mirror image of the left side view;

FIG. 4 is a top view thereof;

FIG. 5 is a cross-sectional view taken on line 5-5 of FIG. 2; and,

FIG. 6 is a bottom view thereof.

The broken lines shown in the drawings illustrate portions of the racket throat that form no part of the claimed design.
